JP 6-304116 11/1994

Primary Examiner—Robert A. Delehanty

(74) Attorney, Agent, or Firm—Harness, Dickey & Pierce,
P.L.C.(57) **CLAIM**

The ornamental design for a power scrubbing device, substantially as shown and described.

DESCRIPTION

FIG. 1 is a perspective view of a power scrubbing device in accordance with the present invention.

FIG. 2 is a front plan view of the scrubbing device of FIG. 1.

FIG. 3 is a rear plan view of the scrubbing device of FIG. 1. FIG. 4 is a right side plan view of the scrubbing device of FIG. 1.

FIG. 5 is a left side plan view of the scrubbing device of FIG. 1.

FIG. 6 is a top plan view of the scrubbing device of FIG. 1; and,

FIG. 7 is a bottom plan view of the scrubbing device of FIG. 1.

The broken line showing of a hose is for illustrative purposes only and forms no part of the claimed design.

UNITED STATES PATENT AND TRADEMARK OFFICE
CERTIFICATE OF CORRECTION

PATENT NO. : Des. 498,027 S
DATED : November 2, 2004
INVENTOR(S) : Alsruhe et al.

Page 1 of 1

It is certified that error appears in the above-identified patent and that said Letters Patent is hereby corrected as shown below:

Title page,

Item [12], "Alsruh et al" should be -- **Alsruhe et al** --.

Item [75], Inventors, "Alsruh" should be -- **Alsruhe** --.

Item [56], **References Cited**, U.S. PATENT DOCUMENTS, reference, "3,398,848", "Doonvan" should be -- Donovan --.

Signed and Sealed this

First Day of March, 2005

JON W. DUDAS
Director of the United States Patent and Trademark Office
